UNITED STATES PATENT OFFICE.

WILLIAM M. GOLDSMITH, OF CINCINNATI, OHIO.

SASH CONSTRUCTION.

1,005,826.

Specification of Letters Patent. Patented Oct. 17, 1911.

Application filed May 10, 1911. Serial No. 626,379.

To all whom it may concern:

Be it known that I, WILLIAM M. GOLDSMITH, a citizen of the United States of America, and resident of Cincinnati, county 5 of Hamilton, and State of Ohio, have invented certain new and useful Improvements in Sash Construction, of which the following is a specification.

The object of my invention is a sash construction, which enables the manufacturer to ship the goods "knock-down" to the building in the course of construction, and which is of a form such that the parts may be easily assembled there.

15 Another object of my invention is a sash construction, the steps of manufacture and assembling of which are inexpensive.

These and other objects I attain by the means described in the specification, and 20 illustrated in the accompanying drawings, in which,

Figure 1 is a part of a sash illustrative of the construction embodying my invention. Figs. 2 and 3 are perspective views of the 25 intersecting members of which the sash is composed, the parts being shown on somewhat an enlarged scale. Fig. 4 is a perspective view of the parts shown in Figs. 2 and 3, in the position they occupy relatively to 30 each other when assembled in a sash.

The sash construction embodying my invention consists of horizontal and vertical interlocking T-bars, which, at the points of intersection, have the flange of one of the 35 intersecting T-bars cut away to pass the flange of its intersecting bar, and have the web of said intersecting bar slotted to pass the web of the first bar.

In the accompanying drawings, I have 40 shown the flanges of the horizontal members as being cut away at intervals, and the webs of the vertical members as being slotted, but I may reverse this order and cut the flanges of the vertical members and the webs of the 45 horizontal ones. The flanges *a* of the horizontal members have a part removed, which is of the width of the flange *b* of the vertical members, the sides *a'* *a''* of the cut in the flange, *a*, being parallel, so as to fit snugly 50 against the sides of the flange *b*. In the web of the horizontal member, midway between the sides *a'* *a''* of the cut, there is formed a notch *a''*. The web *b'* of the vertical members have in them a slot *b''* of a width equal 55 to the width of the web *a''* of the horizontal members, so that the sides of the slots *b''*

fit the sides of the web *a''* snugly. Upon the side of the slot *b''* is a tooth *b''*, which, in the assembled position of the T-bars, fits into the notch *a''*. The tooth *b''* and the notch *a''* have their upper edges at equal distances 60 from the flanges *a* and *b*, so that when the slot *b''* is passed over the flange *a''*, the tooth *b''* will be sprung into the notch *a''* by the elasticity of the metal, at the time when the flanges *a* and *b* become flush with each other 65 in fitting the bars together.

The cut away portions of the flanges of the horizontal members are made at a distance apart, equal to the width of the pane 70 of the sash, and the slots *b''* of the webs of the vertical members are at a distance apart, equal to the height of the pane of the sash.

The manufacturer may ship the T-bars to 75 the building, in which the sashes are to be installed, unassembled. To assemble them, the workman simply has to bring the slotted portion of the webs of the vertical members to register with the webs at the cut away 80 portions of the horizontal members, and then to drive the vertical members to place upon the horizontal members, so that the teeth *b''* fit into the notches *a''*. In this position, the flanges of the T-bars are flush with each other, and together with the webs 85 form a framework into which the panes of glass may be seated.

What I claim is:—

1. A sash construction consisting of T-bars crossing each other, each of said T-bars 90 consisting of a flat flange having parallel faces and parallel edges, and an integral web at right angles to the flange, one of the T-bars at the point of intersection having its flange cut out, the cut-out portion being 95 of the width of the flange of the second T-bar, the second T-bar having its web cut out, the cut-out portion of the web being of the width of the thickness of the web of the first T-bar, the bars being assembled with 100 the web of one embracing the web of the other and with their flanges flush with each other, and a means for locking the T-bars together formed by a notch in the uncut web and a tooth upon the slotted edge of the 105 other web and fitting into the notch.

2. A sash construction consisting of T-bars crossing each other, each of said T-bars consisting of a flat flange having parallel faces and parallel edges, and an integral web at right angles to the flange, one of the T-bars at the point of intersection 110

having its flange cut out, the cut-out portion being of the width of the flange of the second T-bar, the second T-bar having its web cut out, the cut-out portion of the web being of the width of the thickness of the web of the first T-bar, the bars being assembled with the web of one embracing the web of the other and with their flanges flush

with each other, and a means connecting the webs of the T-bars together, said means being integral with the webs.

WILLIAM M. GOLDSMITH.
